CLAIM

The ornamental design for a dilator, as shown and described.

DESCRIPTION

FIG. 1 is a left side perspective view of a dilator of the present invention.

FIG. 2 is a right side perspective view of the dilator of FIG. 1.

FIG. 3 is a front perspective view of the dilator of FIG. 1.

FIG. 4 is a rear perspective view of the dilator of FIG. 1.

FIG. 5 is a top perspective view of the dilator of FIG. 1.

FIG. 6 is a bottom perspective view of the dilator of FIG. 1; and,

FIG. 7 is a three-quarter perspective view of the dilator of FIG. 1.
